UNITED STATES PATENT OFFICE.

MELVILLE R. COLE, OF EUDORA, KANSAS, ASSIGNOR OF ONE TWENTY-FOURTH TO CHAS. B. FLOYD AND ONE TWENTY-FOURTH TO CHAS. L. FULLER, BOTH OF EUDORA, KANSAS, AND ONE-TWELFTH TO FRANK M. BUTLER, OF EXCELSIOR SPRINGS, MISSOURI.

ROAD-WORKING MACHINERY.

1,304,263.

Specification of Letters Patent.

Patented May 20, 1919.

Application filed April 17, 1917. Serial No. 162,672.

To all whom it may concern:

Be it known that I, MELVILLE R. COLE, a citizen of the United States, residing at Eudora, in the county of Douglas, State of Kansas, have invented certain new and useful Improvements in Road-Working Machinery, of which the following is a full and exact specification.

The present invention relates to road-working machinery, and aims to provide an improved construction of apparatus for maintaining proper surface and contour conditions in road beds.

One of the objects of the invention is to devise a simple and efficient machine adapted to shave the surface of the road, together with suitable provision for adjustment for varying the character of the shaving operation for varying conditions of the road bed.

It is also an object to provide an apparatus of this type which will be arranged to deflect the shaved material to one side of the shaved surface, and also equipped with adjustable means for packing said shaved material in its new position.

It is also sought to provide a simple and durable arrangement and construction for accomplishing these results, with a view to employing as few parts as possible and embodying the same in an apparatus which will be economical and inexpensive to manufacture.

With these general objects in view, the invention will now be described with reference to the accompanying drawings illustrating one form of construction for embodying the improvements, after which those features and combinations deemed to be novel will be set forth and defined in the appended claims.

In the drawings—

Figure 1 is a perspective view of an apparatus constructed in accordance with the present invention;

Fig. 2 is a plan view of the same;

Fig. 3 is a side view;

Figs. 4 and 5 are enlarged sectional views taken on the lines IV—IV and V—V, respectively, of Fig. 2;

Fig. 6 is a side view of a portion of the front end of the machine, looking in the opposite direction from Fig. 3 and on a slightly larger scale;

Fig. 7 is a detail section taken on the line VII—VII of Fig. 2 but on a larger scale, and

Fig. 8 is a similar enlarged detail section taken on the line VIII—VIII of Fig. 3.

Referring to the drawings in detail, the supporting framework of the apparatus comprises a front angle bar 2 connected with a yoke casting 4 carried by the flanged wheel 6, to which casting member is connected in a suitable manner a draft tongue 8 and also the front end of a longitudinally extending bar 10. The rear end of the bar 10 is loosely connected to the end of a bolt 12 which is secured to the upright frame piece 14. To this upright member 14 is secured the rear ends of a pair of angle bars 16 and 18, one above the other and inclined toward each other in the direction of the wheel 6 and having their front ends secured to the frame of a rack segment 20, the angle bar 18 being also secured to one end of a transversely extending angle bar 22 the other end of which makes loose pivotal connection by means of a bolt 24 with the extreme outer end of the front bar 2.

The corner of the interior frame work 16—18—22 which carries the rack segment 20 is supported on the bar 10 by means of a roller 26 carried by the lever 28 pivoted at 30 (see Fig. 6) to said interior framework and provided with the spring-actuated pawl 32 for latching engagement with said rack segment. It will thus be apparent that said interior framework may be rocked, by means of said lever, about the bolt connections 12 and 24 and latched in the desired adjusted position.

The framework which has just been described is adapted to support the road shaving means in diagonally extending relation to the road bed. The road shaving tool consists of a two-edged knife or blade 34 having a smooth under surface and secured by bolts 36 to one of the flanges of a steel channel beam 38 in a manner adapting said blade to be carried in almost parallel relation to the road surface for effecting a shaving cut thereon, said blade traveling for the most part below the level of the road surface. 105 The beam 38 is secured about midway between its ends to the lower end of the upright frame piece 14, and at its front end is

provided with a casting 40 having an upwardly projecting arm 42 which is secured to the bolt 24. Secured by bolts 44 to this casting 40 is also provided a nose knife 46 which deviates forwardly from the line of the knife or blade 34 and is provided with a cutting edge which extends upward from the plane of said blade 34. The casting 40 is also formed with a bearing 48 for slidably 5 and pivotally accommodating the angular axle 50 of a caster wheel 52. Also secured to the casting 40 is a bracket 54 pivotally connected by a link 56 with a lever 58 which is mounted on a rack segment 60 fixedly secured 10 to the upper end of the axle 50, said lever carrying the spring-actuated pawl 62 for latching engagement with the rack of said segment 60.

The blade 34 is only about two-thirds the 20 length of the beam 38, the rear portion of the latter permitting the shaved earth material to be deposited in the path of a packing roller 64 which is carried on an axle 66 having the opposite ends thereof supported 25 in boxings 68, one of which boxings is secured by rods 70, 72, and turnbuckle 73 to a plate 74 bolted to said beam 38 adjacent the midportion of the latter; the other boxing 68 is carried by a plate 76 loosely held by a 30 bolt 78 carried by a bracket casting 80 which in turn is secured to the rear end of the beam 38. The roller 64, the opposite ends of which are provided with the flanges 82 for preventing axial movement of the roller, 35 may be adjusted to bring the axis thereof into more or less tilted position with relation to the road bed by means of a crank bolt 84 threaded through said bracket casting 80 into engagement with the plate 76 40 whereby the latter may be swung into different positions with relation to its pivotal support 78, a jam nut 86 being provided for securing said bolt 84 in adjusted position. Obviously also the roller may be adjusted 45 to bring one end of its axle 66 in advance of the other by appropriate adjustment of the turn-buckle 73.

A yoke-shaped seat bar 88 is secured to the beam 38 and bar 16 respectively, and carries 50 a seat 90 in convenient position for enabling the driver to operate the levers 28 and 58.

It will thus be apparent that an efficient and comparatively simple arrangement and 55 construction have been devised for carrying out the desired objects of the invention. The cutting or shaving blade 34, carried in the diagonal relation shown, operates to shave the top surface of the road bed, leaving a 60 smooth and hard surface of the desired contour, and deflecting the shaved material into the path of the roller, which smoothes and packs said material along the middle portion of the road bed. It is found that the 65 operation of this apparatus gives results

superior to those ordinarily obtained by any of the loose earth methods, as it enables the contour outline of the road bed surface to be kept more uniform and more nearly according to the desired outline, and moreover the 70 shaved surface, when treated with oil, absorbs the oil better and gives as nearly a true paved surface as can be obtained with earth and oil. The shaved surface is left firm, hard and smooth and does not require 75 to be packed, but is ready at once for heavy traffic; and, if treated with oil, the surface will drain perfectly, in contrast with loose or imperfectly packed earth after treatment with oil. The lever 28 enables the framework carrying the shaving blade to be tilted about an axis extending substantially longitudinally of the blade so as to present the latter at the proper cutting angle to the road bed; and the blade is also tilted endwise or 80 about a transverse axis by means of the lever 58 operating to raise or lower the front end of the blade, as will be readily understood, this latter adjustment being of course 85 for the purpose of regulating the lateral slope of the road bed. The nose knife 46 serves as an entering element, cutting loose the shaved material at the forward end of the shaving blade and acting to start the deflecting movement of said material along the 90 blade in the direction of its other end. Said blade is detachably mounted on the beam 38, and having the duplex cutting edge arrangement it may obviously be readily removed when one edge has become dull, and re- 100 versed in position and applied with its other cutting edge in position for shaving.

While the foregoing illustrates what is now deemed to constitute the preferred form of embodiment of the improvements, the 105 right is reserved to all such formal changes or modifications as may fairly fall within the scope of the appended claims.

I claim:

1. In a road working machine, a fixed 110 frame comprising longitudinal and transverse bars connected at the front end of the machine, a rocking frame carried within said fixed frame and loosely connected to the free ends of said bars, a road shaving blade 115 carried by said rocking frame in diagonally extending relation to the road, and adjusting means associated with the intermediate portions of said frames and operable to oscillate said rocking frame for varying the 120 cutting angle at which said blade is presented to the road surface.

2. In a road working machine, a fixed 125 frame, a rocking frame carried within said fixed frame and loosely connected thereto, a road shaving blade carried by said rocking frame in diagonally extending relation to the road, and adjusting means carried by one of said frames and having rolling engagement with the other frame, said adjust- 130

ing means being operable to oscillate said rocking frame for varying the cutting angle at which said blade is presented to the road surface.

- 5 3. In a road working machine, a fixed frame comprising longitudinal and transverse bars connected at the front end of the machine, a rocking frame carried within said fixed frame and loosely connected to the free 10 end of said bars, a road shaving blade carried by said rocking frame in diagonally extending relation to the road, and means for oscillating said rocking frame for varying the cutting angle at which said blade is presented to the road surface, said means comprising a lever carried by said rocking frame and provided with a roller in engagement 15 with said longitudinal bar.
4. In a road working machine, a supporting frame, a road shaving blade carried by said frame in diagonally extending relation to the road, and means operative to tilt said blade endwise for adjusting the working position of said blade longitudinally with 20 relation to the road surface, said tilting means comprising a rod having a connection with said frame permitting vertically sliding movement and also rotary movement about a vertical axis, a supporting wheel carried 25 by the lower end of said rod, a rack segment fixedly secured to the upper end of said rod, a lever fulcrumed on said rack segment and 30

having a latching engagement with its rack portion, and a pivotal supporting connection between one end of said lever and said frame. 35

5. A road working machine comprising a supporting frame, a road shaving blade carried by said frame in diagonally extending relation to the road, a packing roller trailed by said frame at the rear of said shaving 40 blade, a vertically swinging bearing supporting one end of said roller, an adjustable stop screw limiting the upward movement of said bearing, and an adjustable connection between the other end of said roller and said 45 supporting frame and operable to adjust the axis of said roller in a horizontal direction about its opposite end.

6. A road working machine comprising a supporting frame, a road shaving blade carried by said frame in diagonally extending relation to the road, a packing roller trailed by said frame at the rear of the rear end portion of said shaving blade, means associated with one end of said roller for angularly adjusting its axis in a vertical direction, and a turnbuckle connection between the other end of said roller and said supporting frame adapted to adjust the axis of said roller in a horizontal direction about the opposite end 60 thereof.

In witness whereof I hereto affix my signature.

MELVILLE R. COLE.
